CLAIM

The ornamental design for a gaming machine, as shown and
described.

DESCRIPTION

FIG. 1 is a front perspective view of a gaming machine
showing my design according to a first embodiment;
FIG. 2 is another front perspective view thereof;
FIG. 3 is a front elevation view thereof;
FIG. 4 is a side elevation view thereof;
FIG. 5 is a front perspective view of a gaming machine
showing my design according to a second embodiment;
FIG. 6 is another front perspective view thereof;
FIG. 7 is a front elevation view thereof; and,
FIG. 8 is a side elevation view thereof.

The dashed broken lines in the figures illustrate portions of
the gaming machine that form no part of the claimed design.
